PUMP GOVERNOR

Malcolm E. Erskine, Racine, Wis., assignor to
Racine Tool and Machine Company, Racine,
Wis., a corporation of Wisconsin

Application May 21, 1934, Serial No. 726,718

2 Claims. (Cl. 103—120)

The invention relates to pump governors and more particularly to a governor for controlling the output of a rotary vane type hydraulic pump.

The object of the invention is to provide a simple mechanism for automatically governing the eccentricity of the outer barrel of a vane type rotary hydraulic pump, so that the pressure of the fluid furnished by the pump will be substantially constant.

10 The invention further consists in the several features hereinafter set forth and more particularly defined by claims at the conclusion hereof.

The drawing shows a vertical sectional view 15 of a rotary vane type pump and the governor mechanism therefor embodying the invention.

The pump herein shown is a vane type rotary pump and more particularly one having a fixed valve shaft, as for example, like the rotary pump 20 of the U. S. patent to Percy O. Ott, No. 1,965,388, dated July 3, 1934.

Briefly the pump includes a valve shaft 2 having an inlet port 3, a discharge port 4 and passages (not shown) in said shaft communicating 25 with said ports and a rotor 5 cooperating with said shaft and provided with passages 6 adapted to be successively brought into communication with said ports in said shaft as the rotor revolves as shown more in detail in said Ott patent.

30 The rotor 5 has a series of vane-guiding and carrying slots 7 in which the vanes or blades 8 are slidably mounted and having outer edges engaging the inner surface of a cylinder barrel or ring 9, said blades dividing the space between 35 the rotor and the ring into a plurality of pumping compartments 10 with which the passages 6 communicate. The blades are preferably held against the barrel by fluid under pressure introduced against the backs of said blades from the discharge line. These blades are substantially 40 radially disposed or slightly offset from a radial line so that as the rotor revolves the barrel or ring 9 will also rotate with it. Parts of the rotor including end plates (not shown) between 45 which the ring 9 is slidably and rotatably fitted are secured together and to the body part 11 of said rotor by bolts 12.

The barrel or ring 9 is mounted to turn freely upon a series of rollers 13 interposed between 50 said ring and an outer race ring 14 which has diametrically disposed flat faces 15 slidably shiftable upon guide bosses 16 on the casing 17.

It is to be noted that shifting of the ring 14 will also shift the barrel 9 and will cause it to 55 be shifted off center relative to the rotor, and

upon the extent of eccentricity thus produced will depend the volume of pressure fluid delivered by the pump and hence its pumping capacity. As shown in the drawing the ring 14 is provided with a rod 18 which extends through a bore 19 in a thimble 20 having threaded bore 21 in the casing 17, said rod 18 having a head including a piston 22 with a spring 23 interposed between said head and the thimble 20 and normally acting on said rod 18 to move it upwardly and thus 10 tend to shift the barrel 9 to one of its positions of greatest eccentricity.

With this type of pump as the rotor 5 revolves clockwise, hydraulic fluid coming in through the inlet port 3 will enter the pumping compartments 10 on the left hand side of said rotor, the volume of these compartments gradually enlarging and then as these compartments pass to the right hand side as viewed in the drawing, they gradually contract in volume while the fluid is 20 forced through the passages 6 to the discharge port 4. It is to be noted that the bore 24 of the rotor body has a working fit with the valve portion of the shaft 2 and that cut off occurs when said rotor is passing the parts 25 of said valve 25 shaft.

As the quantity of the hydraulic fluid increases as the eccentricity of the barrel 9 increases with the rotor revolving at substantially constant speed the pressure of the fluid also increases 30 and to keep the pressure of the fluid substantially constant the pressure of this fluid is caused to act on the barrel 9 to shift it downwardly or in a direction to reduce its eccentricity. For this purpose the piston 22 is mounted to slide in a bore 26 in a barrel or cylinder 27 and is adjustably secured to the upper threaded end 28 of the rod 18 by the nut 29. A washer 23' is preferably interposed between the piston 22 and the spring 23. The upper end of the cylinder 26 40 is closed off by a cap 30 and a pipe 31 leads into the cylinder 26 above the piston so that fluid, at discharge pressure, delivered by the pump acts on the piston 22 and in opposition to the spring 23 so that when the quantity of 45 fluid and consequently the pressure of the fluid delivered by the pump increases above a predetermined value the pressure of this fluid acting against the piston 22 moves said piston downwardly against the action of the spring 23 and 50 thus acts through the rod 18 to reduce the eccentricity of the pump and thus decrease the quantity of fluid delivered by the pump while keeping the pressure substantially constant.

The adjustment of the piston 22 on the rod 18 55

determines the tension of the spring 23 against which the pressure of the fluid acting on the piston has to operate. The thimble 20, it has been noted, has a threaded connection with the 5 casing so that its position may be adjusted relative to the ring member 14 and thus serve as a stop to limit the extreme upper position of said ring when moved by the spring 23. The thimble may also be adjusted so as to stop the movement 10 of the ring member 14 before it reaches a position for full eccentricity of the pump. The size of the piston 22 will vary with the working pressure at which it is desired to have the pump operated.

15 I desire it to be understood that this invention is not to be limited to any particular form or arrangement of parts except in so far as such limitations are included in the claims.

What I claim as my invention is:

20 1. The combination with a pump having a rotor provided with vanes and a barrel cooperating with said vanes and rotor to form a plurality of pumping compartments, said barrel being shiftable to vary the eccentricity of the 25 pump, a support, a cylinder on said support and connected with the discharge of said pump, a piston working in said cylinder in response to

discharge pressure and directly connected to said barrel to shift said barrel toward a position of zero eccentricity, a spring opposing the movement of said piston by the pressure fluid, means including a part of said piston to vary the tension of said spring and a member adjustably mounted on said support for limiting the eccentric position of said barrel. 5

2. The combination with a pump having a rotor provided with vanes and a barrel cooperat- 10 ing with said vanes and rotor to form a plurality of pumping compartments, said barrel being shiftable to vary the eccentricity of the pump, a support, a cylinder on said support and connected with the discharge of said pump, a 15 piston working in said cylinder in response to discharge pressure and directly connected to said barrel to shift said barrel toward a position of zero eccentricity, a member adjustably mounted on said support for limiting the eccentric position of said barrel, a spring opposing the movement of said piston by the pressure fluid and mounted between said member and piston, and means including a part of said piston to vary the tension of said spring. 20 25
